CLAIM

The ornamental design for a laptop stand, as shown and described.

DESCRIPTION

FIG. 1 is a front perspective view of a laptop stand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the laptop stand in a first alternate configuration of use;

FIG. 10 is a perspective view of the laptop stand in a second alternate configuration of use;

FIG. 11 is a perspective view of the laptop stand in a third alternate configuration of use;

FIG. 12 is an enlarged detail view of area 12 in FIG. 1;

FIG. 13 is an enlarged detail view of area 13 in FIG. 2; and,

FIG. 14 is an enlarged detail view of area 14 in FIG. 5.

The broken lines in the drawings illustrate the portions of the laptop stand, which form no part of the claimed design.

The dash-dot-dash broken lines define the boundaries of the enlarged views and form no part of the claimed design.

1 Claim, 14 Drawing Sheets
